UNITED STATES PATENT OFFICE

NELSON K. SMITH, OF LOS ANGELES, CALIFORNIA, ASSIGNOR TO BYRON JACKSON CO.,
OF WEST BERKELEY, CALIFORNIA, A CORPORATION OF DELAWARE

PIPE TONG

Application filed November 6, 1928. Serial No. 317,577.

This invention relates to pipe tongs and, more especially, to that type of tong in which a pivoted gate or latch can be swung into open and closed position, and when closed, is thrust toward the pipe, that is to be held, by a leverage exerted by pivotal movement of the handle of the tong with respect to the body thereof.

One of the important considerations in the production of a tool of this type is to securely clamp the pipe in the tool without crushing the pipe, which crushing would weaken the pipe and undesirably reduce the bore thereof. An object, then, of the invention is to provide for tightly gripping the pipe and at the same time avoid crushing the same.

Another object is celerity with which the tong can be applied to and disengaged from the pipe.

Another important object is to make the tool as automatic in its action as possible.

Although the tool is herein termed "pipe tong," it is to be understood that it is useful for making up and breaking out strings of casing, pump tubing, drill pipe and the like.

The accompanying drawings illustrate the invention:

Fig. 1 is a plan view of a pipe tong constructed in accordance with the provisions of this invention, a portion of the handle being broken away to contract the view.

Fig. 2 is a front elevation of Fig. 1.

Fig. 3 is a horizontal view, mainly in section, viewed from the line indicated by 3-3, Fig. 2.

There is provided a hook-shaped body 6 comprising a curved web 7, top and bottom flanges 8, 9 and transversely extending webs 10, 11. The flanges 8, 9 provide forward curved edges 12 adapted to grip the pipe, that is to be held, on one side. The pipe is gripped on the opposite side by a swinging gate, jaw or latch 13 provided with a curved inner face 14.

The inner face 14 is provided near the free end of the latch with a die 15 which is brought into engagement with the pipe when the latch is in the closed position shown in Fig. 1. In the present instance, the latch 13

is curved so that, when it is closed, its outer face continues the curve of the flange 7.

The jaw 13 is pivoted by a bolt 16 to the body 6 and said body and jaw together constitute a pair of pivotally connected jaws between which the pipe is clamped. The pivot 16 passes through a hole 17 in the latch 13 and through holes 18 in the upper and lower flanges 8, 9. The pivoted end of the latch 13 is interposed between the flanges 8, 9 and said flanges at this point project beyond the web 7 so as to leave a slot 19 through which the pivoted end of the latch can move.

The pivoted end of the latch 13 is provided with a handle comprising a bar 20 and an outwardly projecting arm 21. The bar 20 is secured at its middle to the arm 21 and the opposite ends of said bar project upwardly and downwardly from the arm 21 so that some of the fingers of the operator can be placed on the upper portion of the bar and some on the lower portion.

Near its free end, the latch 13 is provided in its outer face with a recess 22, one wall 75 of which forms a shoulder 23 which is engaged by a shoulder 24 on an operating member 25 which is pivoted at 26 to the body 6. The pivot of the member 25, in this instance, is in the form of a bolt that passes through a hole 27 in the member 25 and through holes 28 in the flanges 8, 9.

The shoulder 24 is formed by one face of a projecting finger 29 of the member 25. The member 25 constitutes the handle of the tong and constitutes a lever adapted when the handle is moved into the position shown in Fig. 1, to thrust the latch 13 inwardly so as to clamp the pipe between the latch and the body 6.

Within the body 6 are spring seats 30, 31 against which seat coil springs 32, 33, respectively. Pivoted at 34 in a recess 35 in the inner end of the latch 13 is a spring seat 36 provided with a shoulder 37 against which the spring 32 thrusts. The prolonged axis of the spring 32 passes on opposite sides of the latch pivot 16 when the latch is in its open and closed positions so as to yieldingly hold said latch in said positions.

Pivoted at 38 in a recess 39 in the inner end of the member 25 is a spring seat 40 provided with a shoulder 41 against which the spring 33 thrusts. The prolonged axis of the spring 33 extends on opposite sides of the pivot 26 when the member 25 is in the retracted position shown in Fig. 3 and in the clamping position shown in Fig. 1 so as to yieldingly hold the body 6 in either 10 of said positions. The springs 32, 33 and pivoted seats 36, 40 may, for brevity, be termed spring toggle devices for yieldingly holding the body 6 and the latch 13 in either one of the positions mentioned above. The 15 pivoted end of the member 25 lies between the flanges 8, 9 and at this point said flanges extend beyond the web 7 so as to form a slot 42 in which the member 25 can operate. One end of the web 7 constitutes a stop 43 20 to limit relative opening movement between the body 6 and handle 25.

In this instance the die 15 is removably mounted in the latch 13, being slidably mounted in an annular hole 44 in said latch. 25 To prevent the die 15 accidentally slipping out of the hole 44, I provide upon the flanges 8, 9 lugs 45 provided with transversely extending holes 46 in which are removably positioned cotter pins 47. 30 To use the invention described above, assuming that the parts are in the positions shown in Fig. 3, the operator grasps the handle 25 and places the tong around the pipe or collar or other cylindrical member 35 that is to be turned or held against turning and he will grasp the handle 20 and by exerting a pull on it, swing the latch 13 into the closed position shown in Fig. 1. Maintaining the grasp on the handle 20, the 40 operator will then swing the handle 25 toward the left in Fig. 3 into the position shown in Fig. 1, thereby causing the shoulder 24 to engage the shoulder 23 and exert pressure of the latch member 13 upon the 45 pipe, thus firmly clamping said pipe by the jaws 6, 13.

To open the tong the operator will swing the handle 25 to the right in Fig. 1, thus causing the shoulder 48 on the inner end of 50 the member 25 to thrust against the inner face of the latch 13, thus swinging said latch outwardly against the pressure of the spring 32. The operator will at the same time grasp the handle 20 and pull thereon so as to start the opening movement of the latch or, at least, so as to swing said latch far enough so that the prolonged axis of the spring 32 will pass to the right of the pivot 16 so that the thrust of the spring 32 will 55 thereafter operate to swing the latch into the fully opened position, as shown in Fig. 3.

I claim:

1. A pipe tong comprising pivotally connected jaws, a lever pivoted to one of said jaws and provided with a shoulder, the other

jaw provided with a shoulder engageable by the first mentioned shoulder when the last mentioned jaw is in closed position and the lever is moved into one of its positions, the jaw with the shoulder and the lever being movable into open positions, spring seats 70 within the first mentioned jaw, springs engaging said seats, other spring seats pivoted to the second mentioned jaw and to the lever and engaged by the springs, the prolonged axis of one of the springs passing on opposite sides of the jaw pivot when the second mentioned jaw is in open and closed positions, and the prolonged axis of the other spring extending on opposite sides of the lever pivot when the lever is in the open and closed positions. 75

2. A pipe tong comprising a body provided with upper and lower flanges and with a web connecting said flanges, there being slots at both ends of said body, a latch pivoted to the body in one of the slots and provided with a shoulder, a lever pivoted to the body in the other slot and provided with a shoulder engageable with the first mentioned shoulder when the latch is in closed position, and spring toggle devices for yieldingly holding the latch and lever in either one of two positions. 80

3. A pipe tong comprising a body having upper and lower flanges and a web connecting said flanges, said body provided with transversely extending webs, the first mentioned web being shorter than the flanges to define end slots in the body, a latch pivoted to the flanges and projecting into one of the slots and provided with a shoulder, a lever pivoted to the flanges and projecting into the other slot and provided with a shoulder engageable with the first mentioned shoulder when the latch is closed and the lever is swung into one of its positions, and spring toggle devices for yieldingly holding the latch and lever in either one of two positions. 85

4. A pipe tong comprising pivotally connected jaws, a lever pivoted to one of said jaws and provided with a shoulder, the other jaw provided with a shoulder engageable by the first mentioned shoulder when the last mentioned jaw is in closed position and the lever is moved into one of its positions, the jaw with the shoulder and the lever being movable into open positions, a spring seat 90 within the first mentioned jaw, a spring engaging said seat, and another spring seat pivoted to the lever and engaged by said spring, the prolonged axis of said spring passing on opposite sides of the lever pivot when the lever is in the open and closed positions. 95

5. A pipe tong comprising pivotally connected jaws, a lever pivoted to one of said jaws and provided with a shoulder, the other jaw provided with a shoulder engageable by

the first mentioned shoulder when the last mentioned jaw is in closed position and the lever is moved into one of its positions, the lever and the jaw with the shoulder being movable into open positions, a spring seat within one of said jaws, a spring engaging said seat, and another spring seat pivoted to the other jaw and engaged by said spring, the prolonged axis of said spring passing on opposite sides of the pivot connecting said jaws when the jaws are in the open and closed positions.

Signed at Los Angeles, Calif., this 30th day of October, 1928.
